Primary Examiner — Sanjeev Paul(74) *Attorney, Agent, or Firm* — Allen, Dyer, Doppelt + Gilchrist, PA(57) **CLAIM**

The ornamental design for an eyeglasses strap, as shown and described.

DESCRIPTION

FIG. 1 is a perspective view of the eyeglasses strap; FIG. 2 is a top plan view of the eyeglasses strap; FIG. 3 is a bottom plan view of the eyeglasses strap; FIG. 4 is a left side view of the eyeglasses strap; FIG. 5 is a right side view of the eyeglasses strap; FIG. 6 is front side view of the eyeglasses strap; and, FIG. 7 is a back side view of the eyeglasses strap. The dashed broken lines define the bounds of the claimed design and form no part thereof.
